ANTONIO COLARUSSO, OF HUDSON, NEW YORK.

CONCRETE-FORM DEVICE.

1,243,713.

Specification of Letters Patent. Patented Oct. 23, 1917.

Application filed January 29, 1917. Serial No. 145,097.

To all whom it may concern:

Be it known that I, ANTONIO COLARUSSO, a citizen of the United States, and resident of Hudson, in the county of Columbia and State of New York, have invented certain new and useful Improvements in Concrete-Form Devices, of which the following is a specification.

My invention relates to improvements in concrete form devices and more particularly to devices serving as a form for the edges of concrete roadways, although it may be found useful in many other situations, including the building of sidewalks, etc.

The main object of the invention is to provide an arrangement which is not only simple and inexpensive, but which may be easily and quickly put in place and adjusted to the desired position and which will remain firmly in place as long as desired and is then easily removed for further operations.

Further and more specific objects, features and advantages will more clearly appear from the detailed description given below, taken in connection with the accompanying drawings which form a part of this specification. The drawing, Figure 1, is an end view of a device embodying the invention in one form. Fig. 2 is the vertical section of a concrete roadway showing the invention in one form in use. Fig. 3 is a side view of the form shown in Fig. 2. Fig. 4 is a side view of the stake forming part of the device shown in Fig. 1. Fig. 5 is an edge view of the hook or supporting member, a side view of which is shown in Fig. 1. Fig. 6 is a detail of the screw threaded member for holding the parts together; and Fig. 7 is a perspective of the nut which locks or holds the parts firmly with relation to one another.

Referring to the various figures, 1 represents a stake, preferably an iron rod tapered at the lower end, so that it may be easily driven into the ground; 2 represents a hook-shaped member adapted to pass around the lower edge of a plank form, 3, and upwardly on both sides of said plank form; 4 represents a screw threaded member which passes loosely through a hole, 5, in the stake 1, the hole 5 not being threaded. The screw threaded member 4 also passes through a hole 6, in the hook shaped member 2, the hole 6 being screw threaded to operatively engage the screw threads on the member 4; 7 represents a nut operating

on the screw threads of the member 4 on the other sides of the stake 1. The screw threaded member 4 may be bent at its outer end as shown in the drawings to form a loop, 60 so that it may be easily turned by inserting through the loop a bar which will serve as a handle. The vertical face of the plank 3 serves as the form for the concrete at the edge of the roadway, sidewalk or the like. 65

In operation, the stakes are driven into the ground at the points desired, either with or without the hook members 2, screw threaded members 4 and nuts 7 in place. After the hook-shaped members 2 and screw threaded 70 members 4 and nuts 7 are put in place, as is illustrated in Fig. 2, the plank forms 3 are then deposited in the hook-shaped supporting members 2. The plank members are then lifted to the desired height and the screw 75 threaded members 4 operated until its inner end firmly engages the plank form 3, so that the latter is held firmly in place at the desired height, it being preferable to have the top of the plank form 3 come even with the 80 top of the concrete roadway. The parts are so arranged that the top of the plank form 3 is as high as or higher than the other parts of the device, so that templets or screeds may be used on top of the plank 85 form 3 without interference from the other parts of the arrangement.

It will be seen from the above that the device will hold the plank forms without the use of nails and is thus economical, both in 90 the saving of nails and the preservation of planks. The arrangement also prevents the sagging of the plank forms, a common occurrence when such forms are nailed to wooden stakes. The device allows the engineer to set his iron stakes with his instrument and the plank forms may then be adjusted thereto in perfect line and grade 95 without disturbing the stakes.

The arrangement can be put up by any 100 laborer and does away with the necessity of a carpenter, which has been customarily required in other devices of this character. The screw member 4 may have a tapered inner end, so that it will bite into the plank 105 member 3 to hold it firmly in the desired adjusted position, that is, if the stake is driven a little too low so that with the plank 3 resting upon the bottom of the hook shaped member 2, the plank form would be 110 too low, the plank form may be raised and held in the desired raised position by oper-

ating the screw threaded member 4 until it engages the plank 3 and secures it in the desired position. The nut 7 may then be tightened up in order to bind the members 1, 2 and 4 firmly together.

Although I have described my improvements in detail with regard to one particular embodiment thereof, I do not desire to be limited to such details, as many changes and modifications may be made without departing from the spirit and scope of my invention in its broader aspects and what I claim as new and desire to secure by Letters Patent is:

15. 1. A concrete form device comprising a stake, a hook member adapted to support a vertical concrete form with the top of the form above the top of the hook member; a screw threaded member passing laterally through the stake and operating laterally through the hook member and adapted to engage the form to hold it firmly in adjusted position and a nut coöperating with the screw threaded member and stake to bind the stake, hook member and screw threaded member rigidly together.

20. 2. A concrete form device comprising a stake, a hook member adapted to support a vertical concrete form, a screw threaded member passing laterally through the stake and operating laterally through the hook member and adapted to engage the form to hold it firmly in adjusted position and a nut coöperating with the screw threaded member and stake to bind the stake, hook member and screw threaded member rigidly together.

30. 3. A concrete form device comprising a stake, a hook member adapted to support a vertical concrete form, with top of the form above the top of the hook member, a screw threaded member passing laterally through the stake and operating laterally through the hook member and a nut coöperating with the screw threaded member and stake to bind the stake, hook member and screw threaded member rigidly together.

40. 4. A concrete form device comprising a stake, a hook member adapted to support a vertical concrete form, with top of the form above the top of the hook member; a screw threaded member passing laterally through the stake and operating laterally through the hook member and adapted to engage the form to hold it firmly in adjusted position.

50. 5. A concrete form device comprising a stake, a hook member adapted to support a vertical concrete form and a screw threaded member passing laterally through the stake and operating laterally through the hook member.

60. 6. A device of the class described comprising a stake, a concrete form member, a member engaging the concrete form member to support it and a screw threaded mem-

ber passing laterally through the stake and supporting member to hold the parts together.

7. A device of the class described comprising a stake, a concrete form member, a member engaging the concrete form member to support it and a screw threaded member passing laterally through the stake and supporting member to hold the parts together, said screw threaded member being adapted to engage the form member to hold the same in any adjusted position.

8. A device of the class described comprising a stake, a concrete form member, a member engaging the concrete form member to support it and a screw threaded member passing laterally through the stake and supporting member to hold the parts together, with the top of the form member above the top of the stake and above the top of the supporting member.

9. A device of the class described comprising a wooden plank form member, a hook shaped member passing under the plank and up on both sides thereof, means for holding the plank in any adjusted position vertically in the hook shaped member and a stake for supporting the hook shaped member.

10. A device of the class described comprising a wooden plank form member, a hook shaped member passing under the plank and up on both sides thereof, means for holding the plank in any adjusted position vertically in the hook shaped member; said means comprising a screw threaded member operating laterally through the hook shaped member and having its end adapted to engage the plank, and a stake for supporting the hook shaped member.

11. A device of the class described comprising a wooden plank form member; a hook shaped member passing under the plank and up on both sides thereof, means for holding the plank in any adjusted position vertically in the hook shaped member and a stake for supporting the hook shaped member and plank with the top edge of the plank higher than any other part of the device.

12. A device of the class described comprising a wooden plank form member; a hook shaped member passing under the plank and up on both sides thereof, means for holding the plank in any adjusted position vertically in the hook shaped member, said means comprising a screw threaded member operating laterally through the hook shaped member and having its end adapted to engage the plank, and a stake for supporting the hook shaped member, and plank with the top edge of the plank higher than any other part of the device.

curing the screw threaded member and stake firmly together.

13. A device of the class described comprising a stake, a concrete form member and a member for holding the form member at various adjusted positions vertically of the holding member and means securing said members together with the top of the form member above the top of the stake and holding member.

14. A device of the class described having in combination, a concrete form member, a U shaped member for holding said form member, means for adjustably securing said form member in said U shaped member in any adjusted position vertically and a stake

for holding said U shaped member and detachably secured thereto.

15. A device of the class described having in combination, a concrete form member, 20 means for holding said form member, means for securing said form member in said holding means in any adjusted position vertically of said holding means, and a stake for holding said holding means and secured 25 thereto.

Signed at Hudson, in the county of Columbia and State of New York, this 19th day of Jan., A. D. 1917.

ANTONIO COLARUSSO.
